UNITED STATES PATENT OFFICE.

STANLEY GASPARAITIS, OF CHICAGO, ILLINOIS.

PRESSURE-FOUNTAIN PAINT-BRUSH.

1,221,170.

Specification of Letters Patent.

Patented Apr. 3, 1917.

Application filed June 5, 1916. Serial No. 101,702.

To all whom it may concern:

Be it known that I, STANLEY GASPARAITIS, a citizen of the United States, and a resident of the city of Chicago, in the county of Cook and State of Illinois, have invented new and useful Improvements in Pressure-Fountain Paint-Brushes; and I do hereby declare that the following is a full, clear, and exact description of the same, reference being had to the accompanying drawings, and to the numerals of reference marked thereon, which form a part of this specification.

In applying paint, varnish, and the like by dipping a brush into a paint or varnish pail and then working the brush over the surface to be painted, a considerable waste occurs due to the fact that in the transfer of the brush from the pail to the surface being painted, quantities of paint drop from the brush, or are splashed therefrom when the brush is actuated. This not only causes a waste of paint but oftentimes cause damage to surfaces where it is not desired.

This invention relates to improvements in painting outfits in which paint is forced from a tank or reservoir by means of an air pump, the paint being fed through the handle of a brush to the bristles thereof through a suitable rubber mouth piece or nozzle having a restricted opening with the mouth piece projecting between the bristles of the brush to evenly supply paint in desired quantities without waste or scattering of the paint.

It is an object of this invention to construct a painting outfit adapted to evenly supply paint to and through a brush from a reservoir tank by air pressure.

It is also an object of this invention to construct a pressure fountain paint brush, adapted to receive paint through the brush handle and through a restricted opening in a flexible mouth piece disposed between the brush bristles.

It is furthermore an object of this invention to construct a painting outfit comprising a paint receptacle having an air pump and a flexible air cylinder associated therewith, adapted to force paint by air pressure through a passaged brush and rubber mouth piece to the brush bristles.

It is finally an object of this invention to construct a fountain paint brush adapted to permit paint to be fed through the brush handle and through a rubber mouth piece on said handle, to the brush bristles by air pressure.

The invention (in a preferred form) is illustrated in the drawings, and hereinafter more fully described.

In the drawings:

Figure 1 is a conventional side view of the device embodying the principles of my invention.

Fig. 2 is a top plan view thereof, with parts omitted.

Fig. 3 is a section taken on line 3—3, of Fig. 2.

Fig. 4, is an enlarged section taken on line 4—4, of Fig. 2.

Fig. 5 is a detail section on line 5—5, of Fig. 1.

Fig. 6 is a section taken on line 6—6, of Fig. 5.

As shown in the drawings:

The device comprises a framework or casting 1, made up of metal strips and angle irons. Pivottally mounted on each side at the upper end of the framework is a ring or attaching loop 2, adapted to be engaged by an adjustable strap 3, for carrying or hanging up the device. Said framework 1, has the angle irons disposed across the sides of its lower end, as clearly shown in Fig. 3, and is open at its upper end to receive a paint can, tank or receptacle 4, therein resting on the horizontal flanges of said angle irons. The can 4, has a centrally disposed concave portion 5, in its upper end, having an aperture therein in which is soldered or otherwise rigidly secured an outwardly threaded stub pipe or nipple 6, adapted to receive a coupling nut 7, threaded thereon to connect one end of a pipe 8, to said can. The bottom of said can 4, is convex and has a large circular central opening to the edges of which is soldered or otherwise rigidly secured an outwardly threaded downwardly projecting rim 9, for a purpose hereinafter described.

Rigidly and removably secured to one side of the framework 1, by means of brackets or metal straps 10, is an air receptacle or cylinder having a centrally apertured top plate 11, the outer edge of which is bent downwardly to afford a circular flange 12. Rigidly secured in the aperture in said top plate 11, is an outwardly threaded nipple or stub pipe 13, to receive a coupling nut 14, to connect the pipe 8, with said air receptacle. The bottom of said air receptacle comprises a base or bottom plate 15, the outer edge of which is bent upwardly to afford a circular flange 16. Secured to said circular flanges 12

and 16, in a manner to prevent air leakage, is a rubber cylinder or tube 17. Formed or rigidly secured in the center of said base plate 15, and projecting inwardly into the 5 air receptacle and downwardly from the plate 15, is an air valve 18, on the lower end of which is threaded a coupling nut 19, to connect one end of a pipe or hose 20, to the air cylinder. The other end of said pipe 20, 10 is connected by means of a coupling nut 21, to the lower end of an air pump comprising a cylindrical casing 22, having a plunger head 23, and plunger rod 24, therein adapted to be moved upwardly and downwardly 15 within said pump casing by means of a handle 25, on the upper end of the rod 24, to pump air into the air receptacle. Said air pump is secured to one side of the frame work 1, adjacent and parallel to the air receptacle by means of metal brackets or 20 straps 26.

Threaded onto the rim 9, of the paint can 4, is a cap 27, having a valve or stop cock 28, secured thereon to control the flow of 25 paint from the can 4, through a hose 29, connected at one end to said valve 28, and having its other end connected to a second valve or stop cock 30, secured to the upper end of a handle 31, of a fountain paint brush. Said 30 handle 31, has a centrally disposed tube 32, extending therethrough, the upper end of which is connected with the valve 30, and the lower end being open and terminating at the 35 lower end of the handle. Connected to the tube 32, on opposite sides thereof and extending obliquely therefrom through the lower end of the handle 31, are auxiliary tubes 33, the lower ends of which are alined with the lower end of the tube 32. The lower end of 40 the handle 31, is provided with a peripheral recess or groove adapted to permit a mouth piece 34, made of rubber or other suitable material to be secured to the handle as clearly shown in Figs. 5 and 6, with the tubes 45 32 and 33, communicating with the interior of said mouth piece, the sides of which converge toward one another until they contact to form lips of a long restricted flexible slit or mouth parallel to the lower end of the 50 handle opposite the lower open ends of the tubes 32 and 33. Also secured by any suitable means in the groove at the lower end of the handle and surrounding the mouth piece 34, are brush bristles 35, of any required kind, the upper ends of which are pressed together by a band 36 of any suitable material secured around the lower portion of the handle to assist in holding the bristles 55 in position.

60 The operation is as follows:

When it is desired to do any painting the device as shown in Fig. 1, may be carried by a painter or operator by means of the strap 3, which may be hung around the neck 65 or over the shoulders of the operator. The

valves 28 and 30, are closed and the air pump is operated by actuating the plunger head 23, in the casing 22, to pump air through the air valve 18, into the air receptacle, the rubber cylinder 17, forming 70 the sides thereof being adapted to stretch to permit the air receptacle to hold air under pressure, the valve 18, being automatically closed by the air pressure in the receptacle. The valves 28 and 30, may now 75 be opened any desired amount. The air under pressure from the air receptacle flows upwardly through the pipe 8, into the paint can 4, forcing the paint downwardly through the valves 28 and 30, and the hose 29, 80 through the tubes 32 and 33, into the rubber mouth piece 34, from which position the paint is forced evenly between the lips of the mouth piece thus saturating the brush bristles 35, with paint, which may now be 85 applied to the surface to be painted in the customary manner. The amount of paint supplied to the brush is of course controlled by the valves 28 and 30.

It is evident from the drawings that the 90 paint can 4, when empty may be replaced by a full can of paint by simply removing the cap 27, and the pipe 8, and that the flow of paint through the lips of the mouth piece 34, is dependent upon the air pressure in 95 the air receptacle and the adjustment of the controlling valves 28 and 30. The flexibility and shape of the mouth piece 34, also tends to close the lips of the mouth piece when paint is not being forced therethrough thus 100 preventing the paint in the mouth piece and tubes 32 and 33 from drying out and clogging the brush.

I am aware that various details of construction may be varied through a wide 105 range without departing from the principles of this invention, and I therefore do not purpose limiting the patent granted otherwise than necessitated by the prior art.

I claim as my invention:

1. In a device of the class described the combination of a portable paint can, with an air pump mounted to one side thereof, an elastic air cylinder mounted adjacent said pump and connected at its bottom with said 115 pump and at its top with said paint can, a brush connected with the bottom of the paint can, controlling valves therefor, and means in the bottom of said elastic air cylinder adapted to admit air under pressure 120 from said pump into said cylinder to force paint from said paint can through said brush when the controlling valves are open.

2. In a device of the class described the combination of a portable frame, a paint 125 can removably supported therein, an air pump mounted on said frame, a paint brush connected with said paint can, controlling valves therefor, an air receptacle connected at its bottom with said pump and at its top 130

with said paint can, an elastic cylinder forming the sides of said receptacle secured to the top and bottom thereof, and an air valve in the bottom of said receptacle adapted to admit air under pressure from said pump into said receptacle to force paint from said can through said brush when said controlling valves are open.

In testimony whereof I have hereunto subscribed my name in the presence of two 13
subscribing witnesses.

STANLEY GASPARAITIS.
